FOLDED STRIP

Abraham Unger, South Orange, N. J., assignor to
 Duro-Persian Mfg. Co., Inc., East Newark, N. J.,
 a corporation of New Jersey

Application October 30, 1945, Serial No. 625,539

4 Claims. (Cl. 57—155)

1

This invention relates to folded strips of flexible ornamental material and is herein disclosed in some detail as embodied in a folded over strip of Cellophane. This particular material is a substantially heat-resistant, water- and oil-insoluble cellulose film or artificial film which may be produced by precipitation of a viscose solution with ammonium salts.

One of the baffling problems of the arts is to put to use the novel properties of new materials which may be thinner than paper, stronger than paper of the same thickness, may carry a glossier finish than paper, are less weakened by wetting with water, are stable in many forms, and are non-fibrous. According to the present invention all these properties of Cellophane and some other materials may be utilized by spirally folding a narrow strip of the material, producing a highly ornamental ribbon which is adapted to be used as a ribbon or may be used in the making of structures such as so-called straw hats, and yet may be produced by a simple process at trivial cost.

The thinnest commercially available Cellophane has been found to provide a material of ample strength for making a product having highly desirable novel characteristics. Such a material is often about 0.0008 inch thick and may be procured carrying the highest conceivable gloss, is amply strong and water-resistant, does not cut threads sewed through it and may be colored black, or some other color, while retaining these characteristics.

That material is strong enough to put through twisting and folding operations without injuring its properties, not tearing as would paper of comparable thickness, and its smoothness and evenness render it ideal for manufacture by automatic machinery.

One highly effective and useful tape has been made by drawing a one-inch strip of the highly glossy opaque black Cellophane over a bar to keep it flat and then twisting it and reeling up the twisted strip so that it flattens as it reels up. A very useful rate of twist was found to be about one per inch of length of strip fed for strip one inch wide. The ribbon may have somewhat irregular foldings thus producing a slight, irregular variation in the final ribbon. With wider or more narrow strip different rates of twist may be utilized depending upon the appearance and construction desired.

While the invention is illustrated as embodied in a Cellophane film either glossy or dull, because that is an exceedingly cheap material widely available commercially, other synthetic or arti-

10 ficial films may be employed if of sufficient strength and thinness to fold without weakening and fold so as to give a flexible ribbon. The article and method of making involve very little labor and hence can be inexpensively made and used for making inexpensive braids, hat bodies, and the like. The method provides a simple and inexpensive way of making braid with unusual stiffness and body.

15 One object of the invention is to provide a highly ornamental ribbon.

Another object is to provide a highly flexible ribbon, nearly waterproof, which carries a high gloss.

20 Another object is to provide a ribbon, the slight irregularities of which contribute to an attractive appearance.

Another object is to provide such a ribbon that it may be produced at low cost and carry the desired properties.

Another object is to provide such a ribbon by utilizing commercially available materials.

Other and further objects of the invention will be obvious upon an understanding of the illustrative embodiment about to be described, or will be indicated in the appended claims, and various advantages not referred to herein will occur to one skilled in the art upon employment of the invention in practice.

25 30 A preferred embodiment of the invention has been chosen for purposes of illustration and description and is shown in the accompanying drawing, forming a part of the specification, wherein:

35 Fig. 1 diagrammatically illustrates a device suitable for producing the ribbon;

Fig. 2 is a diagrammatic sectional view with parts distorted for clarity; and

40 Fig. 3 is a fragmentary face view of an end of the ribbon, partly unfolded to show how the folds may be related to the structure.

45 50 In the form shown a one-inch strip 10 of highly lustrous black Cellophane 300 denier or about 0.0008 inch thick was drawn from a loosely rotating spool or reel 11 by a pair of rollers 12 and 13 so as to feed the strip at a definite speed. The tape then is shown as passing over a flat bar or surface 14 and then passes on to a rotating spool 15 which is shown as adapted to wind up the strip 10 on its flat face while it rotates in a plane parallel to its axis 16 so as to twist or fold the on-coming strip.

The one-inch strip is usually twisted or folded by the turning of the spool 15 at such a rate that it turns about once in every inch it is fed by the

rollers 12 and 13. The turning of the spool and the drawing of the rollers 12 and 13 on the strip as it winds up on the spool causes the strip to flatten out in a flat tape showing inner edges 26 through the thin surface layer, when the described thin Cellophane is used for making the tape.

The resulting tape obtained by twisting the described strip at this speed is roughly $5/32$ to $6/32$ inch wide, varying with the way the folds fall, and with the number of superposed turns on the spool 15. The tape is strong enough to support a weight of a number of pounds, in fact is too strong for an ordinary person to break by a direct pull, is easily sewable, is highly glossy or dull depending on the Cellophane used, uninjured by ordinary wetting, and seems iridescent with various facets formed by the underlying folds, does not crack when folded, and the diagonally running edge is almost invisible, lying close against the tape surface.

The structure of the resulting tape is best shown in Fig. 3, in which the tape 16 is shown unrolled below 17 so that the surface part 18 which lies flat shows the diagonal folds 19 running diagonally of a long side 20. It will be observed, however, that the end 21 which was cut across the axis of the folded tape lies at an acute angle to the side 20 but is at right angles to the folds 19. Thus in effect the tape is made up of bias folds.

The folded tape has a body unattainable in any ordinary way with Cellophane, and retains its folds and body through any ordinary handling and sewing and is exceedingly strong.

While the tape has been primarily described as made from a strip one-inch wide, the method of producing it enables much narrower strips to be folded so that they may be safely handled without danger of unfolding, and moreover enables satisfactory folded strips to be produced commercially much narrower than has hitherto been found possible.

Usually the finished tape shows about one turn lengthwise per unit of width. The narrower widths are very useful for braid and open belting, showing no tendency to unfold, though notably elastic when woven into belts or tapes.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described one embodiment of the invention in some detail, what is claimed is:

1. A flexible and substantially non-stretchable flat twisted ribbon-like tape having a width several times greater than the thickness thereof, comprising a strip of artificial film material disposed in substantially spirally arranged convolutions along the length of said tape and forming at all portions along the length of said tape a plurality of flat superposed layers, each flat layer comprising one side of a single convolution which overlaps the major portion of the immediately underlying layer, said flat superposed layers being

firmly in contact with each other and firmly retained against slippage with respect to each other.

2. A flexible and substantially non-stretchable flat twisted ribbon-like tape having a width several times greater than the thickness thereof, comprising a strip of artificial film material disposed in substantially spirally arranged convolutions along the length of said tape, with the distance between adjacent substantially spirally disposed strip edges being not less than the width of said strip, and forming at all portions along the length of said tape a plurality of flat superposed layers, each flat layer comprising one side of a single convolution which overlaps the major portion of the immediately underlying layer, said flat superposed layers being firmly in contact with each other and firmly retained against slippage with respect to each other.

3. A flexible and substantially non-stretchable flat twisted ribbon-like tape having a width several times greater than the thickness thereof, comprising a strip of artificial film material disposed in substantially spirally arranged convolutions along the length of said tape and forming at all portions along the length of said tape at least five flat superposed layers, each flat layer comprising one side of a single convolution which overlaps the major portion of the immediately underlying layer, said flat superposed layers being firmly in contact with each other and firmly retained against slippage with respect to each other.

4. A flexible and substantially non-stretchable flat twisted ribbon-like tape having a width several times greater than the thickness thereof, comprising a strip of artificial film material disposed in substantially spirally arranged convolutions making about one turn per unit of strip width along the length of said tape and forming at all portions along the length of said tape a plurality of flat superposed layers, each flat layer comprising one side of a single convolution which overlaps the major portion of the immediately underlying layer, said flat superposed layers being firmly in contact with each other and firmly retained against slippage with respect to each other.
